SHANK STIFFENER

Hiram Gordon, Columbus, Ohio, assignor to The
Walker T. Dickerson Company, Columbus,
Ohio, a corporation of Ohio

Application October 10, 1936, Serial No. 105,065

2 Claims. (Cl. 36—76)

This invention relates to shank stiffeners adapted for use in the arch construction of shoes or other articles of footwear, and the object of the invention resides in the provision of an improved shank stiffener comprising an integral blank of sheet metal which may be readily inserted in the arch of a shoe to maintain the desired form and shape thereof and to comfortably support and protect the foot of the wearer.

Another object of the invention resides in the provision of a shank stiffener which while sufficiently flexible to provide for comfort in the use of the shoes in which it is incorporated is formed with a novel reenforcement by which the mechanical strength of the stiffener is materially increased in order to avoid breakage or injury thereto when in use.

For a further understanding of the invention, reference is to be had to the following description and the accompanying drawing, wherein:

Fig. 1 is a perspective view of a shoe shank stiffener constructed in accordance with the present invention;

Fig. 2 is a top plan view thereof;

Fig. 3 is a longitudinal sectional view taken through the arch of a shoe and disclosing the stiffener in its applied or operative position between the insole and outsole of the shoe;

Fig. 4 is a vertical transverse sectional view on the line IV—IV of Fig. 3;

Fig. 5 is a similar view on the plane indicated by the line V—V of Fig. 3.

Referring more particularly to the drawing, the numeral 1 designates the shank stiffener comprising the present invention, the same being formed from one integral piece of sheet metal, preferably steel, and of a length and width adapting it for the type of shoes with which it will be used. In the present instance, the stiffener is of considerably greater width than conventional types of stiffeners and, as shown in Figs. 4 and 5 of the drawing, is of such width as to have its longitudinal edge portions disposed substantially in engagement with the down-turned ribs 2 of a shoe insole 3, the stiffener being disposed in the recess or cavity 4 formed between the bottom of the insole, the inner side walls of the ribs 2 and the upper surface of the outsole 5. Preferably, the stiffener is of such length as to extend throughout the full length of the arch of the shoe from the heel 6 thereof to the forward portion of the outsole. The rear end of the shank stiffener is apertured as at 7 to provide for the passage of customary fastening devices through the heel region of a shoe and, generally, the stiffener is of approxi-

mately the same width throughout the major portion of the length thereof, except that at its forward or lower end, the same is slightly enlarged or flared to provide a cushion-receiving seat 8 or to enter the composition filler 9 usually employed between the insole and outsole at the forward end of the shoe.

In its vertical longitudinal cross section, the shank stiffener conforms substantially to the desired curvature of the arch of the shoe and likewise in transverse section, as indicated in Figs. 4 and 5, the stiffener is slightly concave to accord with the normal transverse curvature of the shoe insole and outsole in the arch region of the shoe. By this construction, the stiffener provides a substantial metallic support in the arch region of the shoe to preserve the shape of the latter as well as increasing the comfort of the wearer by holding the foot in a supported manner.

Another feature resides in reenforcing the stiffener to prevent breakage thereof by stamping the same to include corrugated ribs. These ribs are so located as to provide a central longitudinally extending rib 10 which extends substantially throughout the full length of the stiffener and with supplemental, overlapping angularly disposed ribs 11 and 12 arranged at each side of the central rib 10. The arrangement of these ribs is such as to greatly contribute to the strength of the stiffener and the rigidity of the shoe arch in which the stiffener is incorporated. Moreover, this is accomplished without any substantial increase in weight on the part of the stiffener or the manufacturing costs thereof.

The arrangement of the ribs is such as to enable the stiffener to withstand without breakage the complex stresses and forces applied to the same when the shoe is in use, thus providing a shoe which will retain its shape and comfort after prolonged periods of service. By its construction, the stiffener is firmly retained in its operative position between the insole and outsole and accidental shifting of the same from such position is precluded.

What is claimed is:

1. A metallic arch reenforcing member for shoes comprising a sheet metal stamping formed to constitute a longitudinally arched metallic body extending from the heel to the metatarsal areas of a shoe, the heel end of said member being substantially flat and apertured and the forward metatarsal portion of said member terminating in a flattened and transversely enlarged extension, said member between the heel and metatarsal ends thereof being provided with a single central-

ly disposed longitudinally extending reenforcing rib and at each side of said rib with a pair of shorter diagonally extending reenforcing ribs having overlapping ends.

- 5 2. A metallic arch reenforcing member for shoes comprising a sheet metal stamping formed to constitute a longitudinally arched metallic body extending from the heel to the metatarsal areas of a shoe, the heel end of said member being substantially flat and apertured and the forward metatarsal portion of said member terminating in a flattened and transversely enlarged exten-

sion, said member between the heel and metatarsal ends thereof being provided with a single centrally disposed longitudinally extending reenforcing rib and at each side of said rib with a pair of shorter diagonally extending reenforcing ribs having overlapping ends, the side edges of said member being positioned immediately adjacent and conforming to the configuration of the side walls of the shoe cavity in which the said metallic member is positioned. 10

HIRAM GORDON.
